UNITED STATES PATENT OFFICE

LUTHER C. BALDWIN, OF PROVIDENCE, RHODE ISLAND, ASSIGNOR TO U. S. BOBBIN & SHUTTLE COMPANY, OF PROVIDENCE, RHODE ISLAND, A CORPORATION OF RHODE ISLAND

SHUTTLE TENSION

Application filed October 12, 1928. Serial No. 312,111.

This invention pertains to weaving and relates more particularly to shuttle tensions. In the embodiments of the invention herein chosen for illustration the yarn tensioning 5 elements are housed directly in the wood of the shuttle body as is common practice in large shuttles, such as are employed in duck looms or the like, although certain of the broad features of the invention, as more fully described in my copending application of even date herewith, are capable of embodiment in that type of tension device in which the tensioning elements are carried by or associated with a metallic tension block seated in a cavity of the shuttle bobbin.

In accordance with the present invention the tension device comprises a pair of relatively movable tension plates, the lower of which, as suggested in the copending application of H. A. Davol, Serial No. 229,201, may be fixed in the bottom of a suitable chamber near one end of the shuttle body, such plate preferably having opposed outwardly curled fingers near one of its edges, the fingers constituting the yarn delivery eye of the shuttle. The upper tension element may take any desirable form, but in one illustrated embodiment it consists of a circular cup-like friction shoe having a substantially flat lower surface opposed to the fixed bottom plate and pressed downwardly by an adjustable spring. On the other hand, this upper element may consist of a substantially flat or curved plate, preferably provided with an upturned nose at its inner end, and urged downwardly by an adjustable spring as illustrated, for example, in the Davol application above referred to.

In a preferred arrangement the yarn passes 40 across the opposed surfaces of the tension elements in a substantially straight line and without encountering guides or other elements tending to change its direction, and it is preferred to provide one of the tension elements, for example the fixed lower plate, with means tending to prevent misplacement of the yarn in a forward or rearward direction, when the shuttle is stopped and started.

The yarn delivery eye, constituted by the 50 upwardly curved fingers above referred to, is

provided with a threading opening in its periphery and preferably, although not necessarily, a threading slot in the shuttle body is so arranged as to terminate in substantial registry with the threading opening in the shuttle eye, thus facilitating the delivery of the 55 yarn into the eye.

One difficulty encountered in tensions of this general type is that of keeping the tension elements in proper position relatively 60 to each other and to the shuttle body, since the extremely severe vibration and rapid blows to which the shuttle is subjected in use tends to loosen and dislodge all parts mounted thereon. In accordance with the present 65 invention I provide simple but very effective means for retaining the fixed tension member in position without resort to a multiplicity of bolts or other independent fasteners, thus avoiding the danger incident to the 70 use of such removable fastening elements in a shuttle structure. As one desirable mode of attaining this result I provide the tension chamber in the shuttle body with downwardly divergent walls and force the lower tension 75 plate endwise into the bottom of this chamber so that it is held firmly in place by the overhanging portions of the walls.

Preferably the upper tension element is urged downwardly by means of a spring 80 whose tension may be determined by means of an adjusting screw, and to prevent accidental movement of the adjusting screw I provide suitable locking means, preferably of automatic type, such for example as a spring- 85 pressed detent engageable with a recess in the adjusting screw. In order to guide the yarn into proper engagement with the tension elements, I may provide suitable pins or other usual elements of hardened steel, porcelain, 90 or other wear-resistant material and located at such points as may be desirable for guiding the yarn in the proper direction.

In the accompanying drawings in which certain desirable embodiments of the invention 95 are illustrated,

Fig. 1 is a fragmentary plan view, partly in section, illustrating a preferred embodiment of the invention as applied to a shuttle of the type employed in a duck loom; 100

Fig. 2 is a fragmentary side elevation, partly in section, of the devices shown in Fig. 1;

Fig. 3 is a vertical section substantially on the line 3—3 of Fig. 1;

Fig. 4 is a plan view, to larger scale, showing the lower tension plate removed from the shuttle body;

Fig. 5 is a vertical section, substantially on the line 5—5 of Fig. 4, greatly exaggerating certain features for purposes of illustration;

Fig. 6 is a side elevation of a shuttle provided with tension means of modified form;

Fig. 7 is a fragmentary side elevation showing the opposite side of the shuttle of Fig. 6;

Fig. 8 is a fragmentary plan view of the shuttle of Figs. 6 and 7.

Fig. 9 is a vertical section on the line 4—4 of Fig. 8, certain parts being indicated in dotted lines;

Fig. 10 is a detail elevational view indicating the first step in the formation of a thread delivery opening of the kind shown in Fig. 6, the position of the groove-forming tool being indicated in dotted lines;

Fig. 11 is a fragmentary elevation showing an optional arrangement of the lower friction plate and the undercut delivery chamber; and

Fig. 12 is a view similar to Fig. 11, but illustrating the arrangement of Fig. 6 to larger scale.

Referring first to the arrangement shown in Figs. 6 to 12 of the drawings, the numeral 1 indicates the body portion of a loom shuttle having the nose or end portion 2. This shuttle is provided with a bobbin chamber 3 and with a transverse tension chamber or thread delivery passage 4 which is arranged in the end portion 2 and which is connected to the bobbin chamber 3 by a horizontal slot 5. A curved threading slot 6 is arranged substantially at right angles to the plane of the slot 5, as shown in Figs. 7 and 9.

Upper and lower friction and tension plates 12 and 11 respectively, of hard wear-resistant material for example heat treated steel, are arranged within the chamber 4. A pin 7, having a threaded head engaging the wood of the shuttle body extends upwardly through these plates and is threaded into a retaining nut 9 which engages the end of a spring 10 that yieldingly urges the plate 12 downwardly toward the plate 11. The upper plate 12 is preferably provided with an upturned or rounded edge portion, for example the pointed nose 14, which is adapted to cooperate with the flat upper surface of the plate 11 in providing a flared throat to receive the yarn from the slot 5 and to guide it so that it may readily be drawn between the opposed surfaces of the plates. The lower plate 11 preferably is provided with integral upwardly curved fingers 16 at its outer end, said fingers constituting a yarn delivery eye at the end of the chamber 4 and being adapted to receive and to

guide the thread after it leaves the tension plates.

The tension receiving chamber 4 may be formed initially by the use of any suitable round bit or boring tool so that a round opening extends transversally across the nose portion of the shuttle. Such an opening is indicated by the numeral 18 in Fig. 10. If desired, that end of this delivery passage which is to receive the thread eye may be formed by means of a tool of smaller diameter and may subsequently be enlarged to substantially the shape shown in Fig. 7 so as to accommodate the guide eye composed of the fingers 16 and to permit lateral movement of the thread toward the threading opening provided between the ends of the fingers 16. The larger part of chamber 4, at the right of Fig. 9, is preferably provided with downwardly divergent side walls conveniently formed by the use of a triangular broach or similar tool. This broach is preferably positioned in relation to the original opening 18, as indicated by the dotted lines 20 in Fig. 10. Thus the original round opening 18 is provided with an upper angular recess or groove 21 and with lower recesses or grooves 22 which are opposite each other and which give a maximum width to the opening at its bottom.

The lower friction plate is preferably so dimensioned that it may be driven or forced endwise into firm engagement with the walls of the grooves or undercuts 22. To facilitate this, the edge surfaces of the plate may be beveled, as shown in Fig. 11, so that the plate (here designated 11^a) is substantially trapezoidal in cross section. Alternatively the plate may be left substantially rectangular in cross section and may be driven into place, cutting into or compressing the wood, and when in final position being disposed, as indicated in Figs. 6 and 12.

In either case the opening 4 has side wall portions that are adapted to overhang the edges of the lower friction plate and hold it firmly in place, while the upper groove 21 is disposed above the pointed nose 14 of the upper plate so that the latter is prevented from turning to any substantial extent about the pin 7 as an axis. The lower friction plate is thus anchored firmly in place by its engagement with the wood of the shuttle body while the upper plate is held against objectionable movement by engagement of its nose with the groove 21. When thus mounted the friction plates are held securely in place and will not loosen during use of the shuttle.

Referring now to Figs. 1 to 5 inclusive, which illustrate a preferred embodiment of the invention, the shuttle body 31 having the nose portion 32 is provided with the usual bobbin-receiving chamber 33 and with a transverse tension-receiving chamber 34 (Fig. 3) in its nose portion. A curved, substantially vertical threading slot 36 extends

5 downwardly from the upper surface of the shuttle body into the chamber 34. This slot 36 opens into the bobbin chamber 33 at the point 35 and its other end 35^a (Fig. 2) is preferably disposed substantially in registry with the threading opening in the yarn guide eye as hereinafter more fully described.

10 Preferably the tension-receiving chamber 34 is provided with a lower part having downwardly divergent side walls 34^a conveniently formed like the walls of the opening 4 above described by the use of a broach or the like. In this lower part I mount the lower tension element 41. Preferably the lower tension element 41 is a plate of hard wear-resistant material, for example steel, and this plate 15 preferably is provided with beveled edges 42 (Fig. 5) and is forced or driven endwise into the opposed angular grooves at the bottom of the chamber 34 so that it is firmly and securely retained in position in the same way as the lower tension elements 11 above described. The plate 41 carries a yarn guide eye consisting preferably of integral upwardly curved fingers 46 located at the outer edge 20 of the plate 41, said fingers overlapping at their ends but being spaced to provide a threading opening 47 of more or less helical form extending peripherally into the eye. 25 This opening 47 is preferably disposed in registry with the end 35^a of the thread threading slot 36, as above described, so that the thread drops readily into the delivery eye without opposition.

30 Preferably, for convenience in manufacture, the slot 36 is of circular curvature, and within the arc formed by this slot and concentrically with such arc, if desired, I provide a vertical bore 45 (Figs. 2 and 3) in the wood of the shuttle body, such bore extending downwardly into the chamber 34. Within this bore I dispose an upper tension element 44, preferably of cuplike form having a substantially flat under surface opposed to the upper surface of the plate 41. Preferably 35 the lower edge or corner of the tension element or friction shoe 44 is smoothly rounded, providing a flared throat to facilitate entrance of the thread between the upper and lower friction members. A spring 50 is seated within the cup-like friction shoe 44, and the tension of this spring may be adjusted by means of a screw 49 having threaded engagement with an internally threaded upper portion 40 of the bore 45. In order to hold this screw 49 in adjusted position, I prefer to provide retaining means of automatic type. Thus I may provide a transverse bore 51 in the shuttle body, such bore being internally threaded for the reception of a screw 52 which engages one end of a spring 53 seated within the bore. The other end of the spring bears against a detent member 54 having a tooth adapted to engage any one of a series of recesses 55 formed in the periphery of the screw 45.

49. Similar retaining means may be provided for the nut 9 of Fig. 9.

The plate 41 is preferably provided with an opening 57 wholly to one side of the friction shoe 44, it being noted that in this case the lower tension member is of much larger area than the upper tension member. A guide pin 58 passes through the opening 57 and is firmly secured above and below the plate 41 in the wood of the shuttle body. The pin 58 and the delivery eye comprising the fingers 46 are disposed at opposite sides of the friction shoe 44, and thus cause the yarn to extend in a substantially straight run between the tension members. If desired the plate 41 may be provided with a shallow groove 56 extending from adjacent to the pin 58 substantially to the delivery eye comprising the fingers 46. This groove may, for example, be of the order of one quarter inch in width and one or two thousandths of an inch in depth, this shallow groove being sufficient to exert a slight restraint upon the yarn tending to prevent it from escaping from beneath the upper tension member in a forward or rearward direction when the shuttle is suddenly stopped or started.

If desired, to facilitate removal of the lower tension plate for renewal, I may provide the chamber 34 with an extension or passage 34^b, opening at the opposite side of the shuttle bobbin and through which a suitable tool may be introduced for driving out the lower tension plate.

I claim:

1. A shuttle having a chamber therein, and a tension element in said chamber, the chamber having side wall portions inclined inwardly toward each other and overhanging the tension element for holding the latter firmly in position, the inwardly inclined side wall portions being spaced apart above the tension element to define with the tension element a passage for yarn or thread.

2. A shuttle having a chamber therein, and a tension plate having beveled edges disposed in said chamber, said chamber having opposed wall portions inclined toward each other and in overhanging engagement with said beveled edges, the inclination of the opposed wall portions being substantially the same as the inclination of said beveled edges, thereby firmly holding the plate in position.

3. A shuttle having a transverse opening therethrough, a portion at least of said opening having angular grooves in its opposite side walls, and a tension plate disposed in the bottom of said opening with its edges engaging said grooves, the inner end of the plate being accessible through the opening for engagement by a tool for driving the plate out of the shuttle body.

4. A shuttle having a bobbin chamber, a transverse thread delivery chamber and a slot connecting said chambers, tension ele-

ments in the delivery chamber, a spring tending to hold the tension elements in engagement with each other, and a delivery eye adapted to receive the thread after passing between the tension elements, the delivery chamber having inwardly inclined wall portions which overhang the edges of one of the tension elements and hold the latter firmly in place.

5 10 15 20 25 30 35 40 45 50 55 60 65 70 75 80 85 90 95 100 105 110 115 120 125 130

5. A shuttle having a bobbin chamber, a transverse tension receiving chamber, and a slot connecting the chambers, tension elements in the tension receiving chamber, a spring tending to hold the elements in engagement with each other, an eye adapted to receive the thread after passing between the tension elements, the upper element having a smoothly rounded upturned portion providing a flaring entrance throat to facilitate entry of the yarn between said tension elements, the tension receiving chamber having sides meeting in angular grooves, one at least of said tension elements engaged an opposed pair of such grooves with a driving fit.

6. A shuttle tension comprising a substantially flat lower friction plate, an upper tension element movable toward and from said plate, spring means urging the upper tension element downwardly, and upwardly directed fingers at the outer edge of the lower plate constituting a yarn guide eye, the lower plate having a shallow channel directly below the upper tension element, said channel tending to prevent displacement of the yarn in a forward or rearward direction from below the upper plate.

7. In combination with a shuttle, a tension device comprising opposed relatively movable friction elements of hard wear-resistant material, and means resiliently urging one of said elements toward the other to tension a yarn passing between them, one of said elements having a shallow channel in its surface extending transversely to the length of the shuttle and adapted to oppose escape of the yarn laterally from between the friction elements.

8. A shuttle tension comprising a substantially flat lower plate of wear-resistant material, a cup-like friction shoe having a substantially flat lower surface opposed to the lower plate and of relatively small area as compared to the latter, said cup-like shoe having a smoothly rounded lower edge, a spring within the cup-like shoe normally urging it toward the lower plate, a fixed wear-resistant guide disposed to one side of the cup-like shoe, and means integral with the lower plate constituting a yarn guide eye at the other side of said cup-like shoe.

9. In combination with a shuttle body having a bobbin chamber and a tension receiving chamber, yarn tension means within said latter chamber, a guide eye comprising a pair of

permanently fixed oppositely curved fingers overlapping at their ends and spaced to provide a threading opening, the shuttle body having a curved slot extending from the bobbin chamber into the tension receiving chamber and having its outer end in substantial registry with the threading opening in the guide eye, the threading opening of the guide eye being disposed directly across the end of the curved slot whereby the latter may guide yarn directly into the threading opening of the guide eye.

10. In combination with a shuttle body having a bobbin chamber, a tension chamber, tension means within the tension chamber including a fixed bottom plate, a spring pressed cup-like friction shoe, the bottom plate having upwardly and oppositely curved overlapping arms constituting a guide eye, the ends of said arms being spaced to provide a helical threading opening, the shuttle body having a vertical slot of substantially circular curvature, said slot extending downwardly into the tension chamber, said slot terminating at one end in the bobbin chamber and at its other end substantially registering with the threading opening of the shuttle eye.
